UNITED STATES PATENT OFFICE.

EDWARD L. MOLINEUX, OF NEW YORK, N. Y.

IMPROVEMENT IN PUTTING UP BLUING AND OTHER DYES.

Specification forming part of Letters Patent No. 72,524, dated December 24, 1867.

To all whom it may concern:

Be it known that I, EDWARD L. MOLINEUX, of the city, county, and State of New York, have invented a new and useful Improvement in Preparing and Packing Soluble Colors; and I do hereby declare that the following is a full, clear, and exact description thereof, which will enable others skilled in the art to make and use the same, reference being had to the accompanying drawing, forming part of this specification.

This invention relates to a new and improved method of preparing and packing for sale, transportation, and use a preparation of indigo, or what is known in commerce as "laundry-blue," and other substances of like nature; and the invention consists in providing a bag, constructed of any suitable material and in any suitable manner, wherein the bluing or other article is properly secured; and in providing a box or case, of suitable size and form, and made of metal, wood, or any other suitable material, wherein the bag of soluble blue or dyeing substance is packed, ready for sale, transportation, and use.

The drawing represents a package made up according to my improvement.

A represents the box or package, and which may contain one or more bags; B, the bag which contains the bluing or other dye.

As this article has hitherto been prepared and sold in market, it has usually been in bulk, which rendered it necessary for the consumer to prepare a properly-constructed bag and to transfer the coloring-matter thereto, causing much trouble and inconvenience by soiling the fingers or implements used.

I am aware that, to obviate these objections, the laundry-bluing has been prepared and sold in a liquid form heretofore; but, as the "bluing-bag" is preferred by all laundry-women for imparting the desired color to the water, it is presumed to be the best method, and with the view of preparing the article for market so that it will be ready for safe transportation or use when sold, I have made the improvement described.

By the use of my package a place is at hand for the bag after use, as it is returned to the box or case, instead of soiling a shelf or other article by its contact.

The method of using the bluing-bag is so well understood by those interested that it need not be described, while the method of preparing and packing the article, and articles of a similar nature, for sale and transportation and use possesses advantages which must be obvious to all.

I do not confine myself strictly to the laundry bluing-bag in the application of my improvement, but to all soluble colors which may be imparted to liquids by means of a flexible bag.

Having described my invention, I claim as new and desire to secure by Letters Patent—

The method of preparing and packing soluble dyes or colors, substantially as herein described, and for the purposes set forth.

EDWARD L. MOLINEUX.
